UNITED STATES PATENT OFFICE.

MARTIN SWINTEK, OF DES MOINES, IOWA.

SAND-PUMPING PLANT.

No. 892,329.

Specification of Letters Patent.

Patented June 30, 1908.

Application filed September 25, 1906. Serial No. 336,646.

To all whom it may concern:

Be it known that I, MARTIN SWINTEK, a citizen of the United States of America, and resident of Des Moines, Polk county, Iowa, have invented a new and useful Sand-Pumping Plant, of which the following is a specification.

The object of this invention is to provide improved means for gathering, elevating, washing, screening, storing, grading and delivering sand.

My invention consists in the construction, arrangement and combination of elements hereinafter set forth, pointed out in my claims and illustrated by the accompanying drawing, in which—

Figure 1 is a plan of the complete apparatus, or plant. Fig. 2 is a side elevation of the screening, storing and delivering portions of the plant, portions broken away to economize space. Fig. 3 is a vertical section on the indicated line 3—3 of Fig. 2.

In the construction of the apparatus as shown the numerals 10, 11, 12 and 13 designate bins supported on posts 14 in such manner that the contents thereof may be deposited by gravity in cars on railway tracks 15, 16 alongside said bins. The bins 10, 11 are arranged in parallel rows contiguous each other and are spaced apart longitudinally from the bins 12, 13. An apron 17 is mounted on and extends longitudinally of and upward from the initial end portion of the bins 10, 11, and that portion of the bins 10, 11 adjacent the apron is higher than the opposite end portion thereof. The outer side walls 18, 19 (Fig. 3) of the bins 10, 11 are extended above the partitions 20 transversely thereof, as is also the longitudinal partition 21 between said bins, the latter partition also provided with a plank or walk 22 on its top. Egress ports for each of the bins 10, 11 are formed in the side walls 18, 19 and normally are closed by gates 23, 24 mounted slidingly in bearings on the outer faces of said walls. The bins 10, 11 are provided with hopper bottoms inclined toward the egress openings. The gates 23, 24 are connected by rods 25, 26 to levers 27, 28 fulcrumed on the tops of the side walls 18, 19 and adapted for manual actuation individually to open the egress ports of individual bins. There is one gate, one rod and one lever provided for each bin 10 or 11. Chutes 29, 30 are hinged at their inner ends to the lower portions of the side

walls 18, 19 adjacent and in front of the egress ports of the bins 10, 11 and said chutes are connected by cables 31, 32 to shafts 33, 34 above them, said shafts journaled in horizontal positions on the outer walls 18, 19 of the bins and provided with cranks 35, 36 on one end. A platform 37 is mounted between the bins in such position that an operator standing on said platform can manipulate the cranks 35, 36. The platform 37 may be reached by a ladder 38, and another ladder (not shown) may be provided between said platform and the top of the bins. The bins 12, 13 also are provided with egress ports, gates 39, rods 40, levers 41, chutes 42, cables 43 and crank shafts 44 adapted to be operated manually from the platform 37.

A hopper 45 is supported from and above the apron 17 and is open and communicates at one side with the upper end portion of an inclined screen 46, the lower end portion of said screen extending over on the bins 12, 13. The screen 46 may be of any desired mesh and may be mounted removably and replaceably in order that another of different mesh may be substituted therefor when desired. A deflector 47 is hinged at its lower end to the central partition 21 and extends across the apron 17. The deflector may be placed in any desired position on the apron and served to guide and direct sand on the apron into either the bins 10 or 11. A trough 48 is provided at the lower end portion of the row of bins 10, 11 and a water pipe or overflow conduit 49 leads from one end of said trough. A scow 50 is moored adjacent the bins, as may be convenient, and a pump-house 51 is carried thereby. A pump 52 is carried by the scow 50 within the house 51 and is driven by any desired power, in this instance by an engine in the pump house fed by steam through a pipe 53 from a boiler or boilers in a house 54 on the land. A receiving pipe 55 made in sections flexibly connected by joints 56, is supported on scows 57, 58, 59. One end of the pipe 55 communicates with the pump 52 and the opposite end thereof is fitted with a suction mouth 60 connected by a cable to a drum (not shown) in the pump house. The outermost section of the pipe 55 and the mouth thereon may be raised and lowered by the cable 61 to adapt said mouth to the bed over which it is designed to work. A delivery pipe 62 leads from the pump 52 to the hopper 45 and is made in sections flexibly connected by joints 63. The delivery pipe

62, is suitably supported between the pump and hopper. The scow 59 is attached to a cable 64 and said cable is rove through sheaves 65, 66 longitudinally removed from the scow 50 and is adapted to be connected to a drum (not shown) in the pump house. By means of the cable 64 the scow 59 may be moved in an orbit relative to the pump, and the scows 57, 58 move with it under the influence of the 10 receiving pipe 55 supported thereon.

In practical use the sand and water can be pumped from the bed of a stream or body of water through the mouth 60, pipe 55, pump 52 and pipe 62 and be delivered to the hopper 45 per 45. From the hopper 45 the water and sand flows by gravity upon the screen 46, the coarse sand and gravel running from said screen into the bins 12, 13 and the finer sand and water falling through said screen upon the apron 17, from whence it is guided, as desired, by the deflector into the bins 10 or 11 or into both by removing said deflector. The first bins fill and overflow into the second and so on throughout the series of bins until the 25 end is reached and the surplus water overflows from the last bins into the trough 48 and off through the pipe 49, carrying with it the lighter grades of undesirable sand and the refuse such as leaves, sticks and dirt that may 30 pass through the screen. As desired the chutes are lowered by hand through the use of the crank shafts and cables, the gates are individually raised by manipulation of individual levers, and the sand or gravel or both 35 is drawn from the bins into vehicles, such as railway cars, for transportation to points of use. When allowed to stand for a time the water drains from the sand in the bins through the egress ports and around the 40 gates thereof. One or more bins only may be opened as desired.

I claim as my invention—

1. In a sand pumping plant, a pair of bins arranged side by side, a series of bins arranged 45 in pairs in side by side relation and having the initial pair thereof spaced from said first named pair of bins, an inclined apron disposed in said space between the bins and leading from said first named pair of bins 50 downwardly to said initial pair of the series, a hopper supported by and above said apron at a point intermediate of the length thereof, an inclined screen overlying the apron and leading from one end of said hopper downwardly to said first named pair of bins, and a 55

deflector operating on said apron and beneath said hopper, said deflector being pivoted at the dividing line between the pairs of bins of said series of bins, and means for delivering sand suspended in water to said hopper having its discharging point to one side of either of the two extreme positions of said deflector. 60

2. In a sand pumping plant, a pair of bins, a series of bins arranged in pairs and having 65 the initial pair thereof spaced from said first named pair of bins, a longitudinal partition dividing said series of bins, said series of bins being at a lower elevation than said pair of bins, an inclined apron in said space leading 70 from said pair of bins downwardly to said initial pair of the series, a hopper at a distance above and overlying said apron, means for supporting said hopper from said apron, a screen leading from said hopper downwardly 75 to said pair of bins, said screen overlying said apron, and means on the apron leading from said partition to the sides of said apron to direct the discharge from said screen, and means for delivering sand suspended in water 80 to said hopper having its discharging point to one side of either of the two extreme positions of said directing means.

3. In a sand pumping plant, a pair of bins and a series of pairs of bins with a space between said pair of bins and the initial pair of said series of bins, an apron having converging sides leading from said pair of bins downwardly to said initial pair of the series, a hopper overlying said apron and spaced 85 therefrom and located approximately central of the length of said apron, a screen overlying the apron leading from said hopper downwardly to said pair of bins, and a deflector pivoted at one end at a point between 90 said bins of the initial pair of the series and at its opposite end being adapted for engagement with said converging sides of the apron at points beyond the initial point of discharge 95 of the screen, and means for delivering sand suspended in water to said hopper having its discharging point to one side of either of the two extreme positions of said deflector.

Signed by me at Des Moines, Iowa, this 27th day of August, 1906.

MARTIN SWINTEK.
